PURSE HOLDER OR SIMILAR ARTICLE

Kenneth G. Bride, 408 Brett St.,
Inglewood, Calif. 90302

Filed Nov. 15, 1971, Ser. No. 199,085

Term of patent 14 years

Int. Cl. D3—02

U.S. Cl. D87—2 A

FIG. 1 is a side elevational view of a purse holder showing my new design, the side opposite being a mirror image thereof, the broken line showing of a table edge being for purposes of illustration only; and

FIG. 2 is a rear elevational view of the purse holder.
I claim:

The ornamental design for a purse holder or similar article, substantially as shown and described.
